MOP CONSTRUCTED OF YARNS ARRANGED
IN LATERALLY SPACED-APART GROUPS

Herbert R. Kirby, Los Angeles, Calif.

Application February 12, 1947, Serial No. 727,969

4 Claims. (Cl. 15—229)

1

This invention relates generally to mops and refers more particularly to mops of the type employed to apply liquids at elevated temperatures.

Mops forming the subject matter of this invention are especially useful in the fabrication of roofing or decking where layers of roofing felt are laid down in superposed relation and are coated with asphalt, tar or pitch to assure a moisture-tight bond between adjacent layers. In fabricating roofing of the above general types, it is important to apply a uniform and thin coat of the bonding material over the felt in order to prevent trapping air bubbles within the coating and between the layers of felt and to provide a weatherproof roof. The coating material must be in a highly fluid state and, because of this, is usually heated to a temperature above 400° F. before it is applied.

Difficulty has been experienced in the past in providing a mop which combines the properties of being sufficiently light in weight to be readily maneuverable, of being capable of withstanding elevated temperatures for extended periods of use, and of having the liquid retention qualities necessary to cover a substantial area without redipping in the liquid. The difficulty arose from making the mop head of fibrous glass to obtain the desired resistance to high temperature, but since the smooth, non-porous glass fibers are non-absorbent and can carry liquids only on their surfaces and by capillary action, a substantial increase in the quantity and weight of fibrous material was indicated to provide high capacity for retaining liquids.

It is an object of this invention to provide a mop having a head comprising a mass of fibers that are unaffected by the temperatures of 400° F. and above that are encountered in the application of roofing materials but having the desired high capacity to retain liquids.

It is another object of the invention to provide a mop head in which the yarns or strings throughout the head are exposed to liquids when the mop is dipped into a body of liquid.

It is another object of the invention to provide a mop head having a greater overall bulk for the amount or weight of the fibrous material making up the head.

It is a further object to provide a mop head that has greater liquid holding ability in the regions adjacent the upper end of the head so that such regions act as a reservoir for liquid that feeds down into the lower end of the head during a mopping operation.

It is still another object of the invention to provide a mop head formed of fibrous glass having means for securely holding the relatively smooth, slippery glass fiber yarns against pulling out from the head during use of the mop.

The foregoing as well as other objects will be

2

made more apparent as this description proceeds, especially when considered with the accompanying drawings, wherein:

Figure 1 is a side elevational view of a mop constructed in accordance with this invention;

Figure 2 is an elevational view of the mop head showing the inner core of relatively short fibers;

Figure 3 is a sectional view through the mop head;

10 Figure 4 is a cross sectional view taken on the plane indicated by the line 4—4 of Figure 1;

Figure 5 is an elevational view showing one step in the method of forming the mop head;

15 Figure 6 is a side elevational view showing another step in the method of manufacture;

Figure 7 is a sectional view taken on the line 7—7 of Figure 4;

20 Figure 8 is a perspective view of parts of a modified mop;

20 Figure 9 is an elevational view of the body of fibers employed in making the mop shown in Figure 8;

Figure 10 is a cross sectional view taken on the line 10—10 of Figure 9;

25 Figure 11 is an elevational detail view, partly broken away, showing a modification in the manner of arranging the mop yarns, and

Figure 12 is a fragmentary sectional view illustrating an assembly of the components of the 30 invention illustrated in Figure 8.

The mop featured in the embodiment of the invention shown in Figures 1 to 7, inclusive, comprises a head 15, a handle 16 and connecting means 17 for removably securing the mop head

35 to the handle. The mop head 15 comprises a tubular holder 18, a body 19 of mop yarns and a retainer 20 for the fibers in the form of a flexible tape 21. The holder 18 is preferably formed of metal or some equivalent strong, light-weight

40 material and is provided with a pair of holes 22 at diametrically opposite sides thereof. The internal diameter of the holder 18 is sufficient to freely receive the lower end portion of a sleeve 23 having a pair of diametrically opposed holes

45 24 adjacent the lower end registerable with the holes 22 in the holder for receiving a pin 25. The pin 25 extends transversely through the registering holes and serves to detachably secure the holder to the sleeve.

50 As shown in Figure 4 of the drawings the outside diameter of the sleeve 23 is smaller than the inside diameter of the holder 18 and four spacers 26 are welded or otherwise secured to the sleeve in spaced relation to each other circumferentially of the sleeve 23. The spacers 26 take up the clearance between adjacent walls of the holder and sleeve and provide a snug fit of the sleeve 23 in the holder 18. The upper end of the sleeve 23 is adapted to receive the lower end 55 portion of the mop handle 16 which is preferably

formed of wood or other material. In the present instance the handle is secured to the sleeve by a pin or bolt 27 extending through registering openings formed in the handle and in diametrically opposite sides of the sleeve 23.

In general the body 19 is formed of a multiplicity of yarns or cords grouped around the holder 18 in sheets or layers that depend from the holder and are disposed one within the other and spaced laterally from each other to provide annular spaces between the sheets or layers. Preferably the yarns or cords at the center of the body 19 are substantially shorter in length than the yarns in the remainder of the body to provide a central opening in the body of the mop head. This central space and the spaces between the sheets or layers of yarns greatly increase the capacity of the mop head to hold a coating liquid because they enable the liquid to readily collect on practically all of the available surface area of the yarns and the fibers in the yarns when the mop head is immersed in the liquid.

The yarns or cords making up the fibrous body 19 are composed of intertwined glass fibers so that the mop is highly resistant to heat and particularly to the temperatures normally encountered in the application of molten roofing materials. Especially satisfactory results have been obtained by using fibrous glass in which the individual fibers are sufficiently fine to provide the high liquid holding capacity required in mops of this character and that are collected together into cords of sufficient size to provide the relatively large bulk also desired in such mops. For example, each strand or yarn may be in the form of an intertwined body of fine glass fibers, each having a diameter of about .0003 of an inch or less. The large aggregate surface area relative to the bulk of a mass of these very fine fibers results in a mop having a greater holding capacity for liquids. Since the fibers themselves are non-absorbent, the liquid is readily available to be transferred from the mop to a surface to be coated, and only a small amount of liquid remains in the mop after a mopping operation. Moreover, the glass of the fibers has a sufficiently high rate of heat conductance, so that any asphalt remaining in the mop after a mopping operation and that has hardened, will readily soften under the application of heat when the mop is reused.

In practice, a retainer 28 in the form of a relatively narrow tape of interwoven glass or other fibers is placed on a flat work surface, and a plurality of bundles 29 of generally parallelly arranged glass fiber yarns of desired length are placed side by side across the length of the tape. In the particular illustration shown in Figure 5 of the drawings, eight bundles of yarns are employed and these bundles are laid across the tape in juxtaposition to each other. The number of bundles and size of the bundles is selected to provide the weight of fibrous material desired in the mop head, usually 6 to 12 pounds. Several of the end bundles, usually the two end bundles 30 and 31, are laid symmetrically with respect to the longitudinal center line of the tape. The remaining bundles 32, as illustrated in Figure 5, are longer than bundles 30 and 31 and are shifted laterally with respect to the tape, so that the length of the end portions 33 projecting beyond the adjacent longitudinal edge of the tape is considerably less than the length of the end portions 34 extending beyond the opposite longitudinal edge of the tape.

After the bundles 29 of strands are positioned

across the tape in the above manner, they are flattened and smoothed down to form a sheet or layer of uniform thickness. The length of the tape extending beyond the bundles is then folded over the top of the bundles, or a second length of tape is laid over the bundles, and the free ends 34 of the tape are folded inwardly. The folded tape is then sewn or stitched along its center line and then along its longitudinal edges to securely fasten the strands forming the bundles in place. Upon completion of this operation, the assembly is folded along the longitudinal center line of the tape in the manner indicated in Figure 6 of the drawings to form the body 19.

In the modified form of the invention shown in Figure 11, the bundles 29 of strands are of double length and are folded over at their centers as at 50. The doubled over portions are laid side by side crosswise of the tape 28. This eliminates the short ends 33 and assures against pulling out of the strands during use of the mop.

When the tape or retainer 28 with the strands secured thereto is folded about its longitudinal center line, the relatively short ends 33 of the bundles 32 assume positions immediately adjacent the much longer end portions 34 and the end bundles 30 and 31 are folded midway between their ends to form double layers somewhat shorter in length than the length of the portions 34 of the bundles 32. After the retainer or tape 28 is folded in the above manner, the end of the tape adjacent the bundles 30 and 31 is positioned against the holder 18 and the tape is wrapped around the holder to form a substantially flat spiral with the fibrous strands extending downwardly from the holder. The length of the tape 28 taken up by the bundles 30 and 31 is preferably sufficient to extend around the circumference of the holder 18 to form a central portion of the mop head. This head is surrounded by the substantially longer layers of yarns in the bundles 32. This difference in length of the glass fiber strands provides a central opening or space 35 for entry of the coating liquid into contact with the inner regions of the mop head. Also, it will be noted from Figure 3 of the drawings that the relatively short ends 33 of the layers composed of the fibrous glass bundles 32 act as spacers between adjacent convolutions of the layers composed of the end portions 34 of the bundles 29 to form the spaces 36 between these layers. The spaces 36 afford ready access of a coating liquid to the surfaces of the yarns throughout the mop head to greatly increase the capacity of the mop to retain liquid.

The spirally wound body 19 is held in assembled relation with the holder 18 by a clamp in the form of a length of wire 37 wrapped around the tape 28 and twisted at the ends. Also in the present instance, four lengths of wire 38 are passed through four equally spaced openings 38' formed in the holder 18 above the retainer or tape 28. The lower end portions of the four lengths of wire 38 are bent upwardly around the lower edge of the holder 18 over the spirally wound tape 28 and are secured in place by twisting their ends together. This is one of many types of fastening means that may be used to secure the body 19 of the mop head to the holder 18 and the invention is not to be restricted to the specific means shown.

The embodiment of the invention shown in Figures 8 to 10 inclusive features another attachment of a mop head to a handle assembly. In this embodiment of the invention a skein of glass

fibers is arranged to form a rectangular flat sheet or body 40 of yarns or cords of glass fibers. Tapes 41 also of fibrous glass are fastened to the body 40 by being stitched to opposite faces thereof along the middle of the body. The body 40 is then folded over along its longitudinal center line and is stitched as at 42 to fasten the two sides of the body together and to form a loop 43 at the upper end thereof.

The folded body 40 is adapted to be attached to a handle 44 by a retainer or support 45 in the form of a metal strip bent into the shape of a spiral and having the inner end pinned or otherwise secured to the lower end of the handle 44. The loop 43 on the folded body 40 is of sufficient size to enable threading the same onto the spiral retainer 45 to provide a mop head with adjacent convolutions of downwardly extending glass fibers. The retainer positions the adjacent convolutions of glass fibers in lateral spaced-apart relationship to provide ample clearance between the yarns for the entrance of the coating liquid with which the mop is used.

Mops fabricated of glass fibers collected in strands and yarns in accordance with either of the above embodiments have a compact and dense nature, because of the compact arrangement of the individual smooth fibers in the cords, but at the same time, provides a "feather edge" effect at the lower end of the mop due to unravelling of the cords at their extremities. This separation of the fibers at the ends of the cords aids materially in obtaining a very uniform coating of liquid on the surface being mopped. It will further be noted that in both embodiments of this invention, provision is made for readily removing the mop head from and assembling the mop head on the handle assembly whenever it is desired or necessary to replace the mop head.

I claim:

1. As an article of manufacture, a mop head comprising a layer of glass fibers folded upon itself with the fold being substantially along a median line for a portion of the length of the layer and along another portion of the layer being offset to one side of the median line of the second-named portion, the folded layer being rolled upon itself with the portion folded on the median line arranged inside of the said other folded portion to provide a plurality of substantially annular sections arranged one within the other and having the fibers extending from an inner section substantially shorter in length than the fibers extending from an outer section.

2. As an article of manufacture, a mop head comprising a holder, a substantially circularly arranged mass of glass fibers all extending in side by side relation, a portion of said mass at one end thereof being folded over on itself along a line to provide a double thickness at said end and another portion of said mass being of different length folded over on itself along the line and extending in the same general direction, a retainer in the form of a flexible tape secured to said mass along the line of the fold thereof and extending spirally around the holder in a plurality of convolutions, the fibers extending from the innermost convolutions being shorter in length than the fibers extending from the outer convolutions to provide a central space in the mass of fibers, and the adjacent convolutions made up of the longer fibers being spaced apart

laterally to provide additional spaces in the mass of fibers.

3. As an article of manufacture, a mop head comprising a holder, a mass of glass fibers arranged in side by side relation, a retainer for supporting the fibers extending in a substantially flat spiral around the holder in a plurality of convolutions with the fibers extending from one convolution spaced crosswise of the mop head from fibers extending from adjacent convolutions, the fibers in an outer convolution extending a greater distance from the retainer than fibers extending from the innermost convolution.
4. As an article of manufacture, a mop head comprising a holder, a mass of yarns formed of glass fibers, said yarns extending in side by side relation forming a sheet, a portion of said mass at one end thereof being folded over on itself along a median line to provide a double thickness at said end and another portion of said mass being offset from the median line and folded over on itself along the median line, a retainer in the form of a flexible tape secured to said mass along the line of the fold thereof and extending spirally around the holder in a plurality of convolutions, the yarns extending from the innermost convolutions being shorter in length than the yarns extending from the outer convolutions to provide a central space in the mass of yarns, and the adjacent convolutions made up of the longer yarns being spaced apart laterally to provide additional spaces in the mass of yarns.
